CLAIM

The ornamental design for a charging box, as shown and described.

DESCRIPTION

FIG. 1 is a front elevation view of a charging box showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view, in an open position, thereof;

FIG. 8 is a perspective view of a second embodiment of a charging box showing my new design in an open position, the elevation/plan view of the six faces are the same as the first embodiment;

FIG. 9 is an enlarged view of the charging box taken from the circle portion in FIG. 1; and,

FIG. 10 is an enlarged view of the charging box taken from the circle portion in FIG. 6.

The broken lines encircling the detail portions in FIGS. 1 and 6 illustrate the boundaries of the detail portions, and form no part of the claimed design; and the other broken lines in the drawings depict portions of the charging box and form no part of the claimed design.

1 Claim, 10 Drawing Sheets
